UNITED STATES PATENT OFFICE

167,015

GLASS GOBLET

William A. Wood, Jeannette, Pa., assignor to McKee Glass Company, Jeannette, Pa., a corporation of Pennsylvania

Application September 13, 1950, Serial No. 12,167

Term of patent 14 years

(Cl. D36—8)

To all whom it may concern:

Be it known that I, William A. Wood, a citizen of the United States, residing at Jeannette, county of Westmoreland, State of Pennsylvania, have invented a new, original, and ornamental Design for Glass Goblet, of which the following is a specification, reference being had to the accompanying drawing, forming a part hereof, in which:

Fig. 1 is a perspective view of a glass goblet showing my new design;

Fig. 2 is a sectional view through the stem taken on line 2—2 of Fig. 1; and

Fig. 3 is a fragmentary vertical sectional view thereof on line 3—3 of Fig. 2.

I claim:

The ornamental design for a glass goblet, substantially as shown.

WILLIAM A. WOOD.
